GOLF PUTTING INSTRUCTIONAL DEVICE

Marvin E. Chidester, P.O. Box 565,
Elberton, Ga. 30635

Filed Aug. 31, 1967, Ser. No. 8,450

Term of patent 14 years

(Cl. D34—5)

FIG. 1

FIG. 2

FIG. 3

FIG. 4

FIG. 5

FIG. 6

FIGURE 1 is a top plan view of the golf putting device showing my new design;

FIGURE 2 is a bottom view of the golf putting device;

FIGURE 3 is a front view of the device of the invention shown in FIGURES 1 and 2;

FIGURE 4 is a rear view of the device shown in FIGURES 1 and 2;

FIGURE 5 is an end view of the device shown in FIGURES 1 and 2, the other end being substantially identical; and

FIGURE 6 is a perspective view of the golf putting device of the present invention shown in FIGURES 1-5.

The broken line showing of a conventional golf ball in FIGS. 5 and 6 is for illustrative purposes only.

I claim:

The ornamental design for a golf putting instructional device, as shown and described.
